D1504

Improvement in Clock Case & Clock Case Front
By Elias Ingram of Bristol Conn 7861

Patented Dec 3, 1861.

E. H. Griswold
Eliza H. Griswold
Griswoldville Conn 7861

Dec. 1504

Elias engraver of Bristol Conn.
Nov. 16, 1864. Letters Patent No. 139 dated Dec. 3, 1861.

The schedule referred to in these Letters Patent and making part of the same.

To whom it may concern:

Be it known that I, Elias engraver of Bristol County of Hartford, and State of Connecticut, have invented or produced a new and original design for a Clock Case, and I do hereby declare that the following is a full and exact description of the same, reference being had to the photographic views, in which the same letters indicate like parts.

In the accompanying photographic views, are shown a new and original design for a clock case.

A. is a plain round surface, constituting the upper member.

B. is a plain round surface constituting the lower member.

C. are plain round blocks of relief, combined with A & B, at their angle, or junction, to form the case proper.

D. is a plain round, or curved face frame for the dial &c.

E. is a plain round or curved face frame for the lower member.

F. are plain figured relief rosettes, at the angle or junction of the upper and lower members D & E, to form a sash or design of a case complete.

What I claim and desire to secure by Letters Patent, is -

The design for a clock case as herein before illustrated and described.

W. Bassett.
E. W. Givensold.
Jeremy W. Blis.

Elias engraver.
